UNITED STATES PATENT OFFICE.

FREDERIC BARR, OF NEW YORK, N. Y.

ELECTRIC SWITCH.

1,053,552.

Specification of Letters Patent. Patented Feb. 18, 1913.

Application filed February 15, 1911. Serial No. 608,656.

To all whom it may concern:

Be it known that I, FREDERIC BARR, a citizen of the United States, and a resident of New York, in the county of Kings and State of New York, have invented certain new and useful Improvements in Electric Switches, of which the following is a specification.

My invention relates particularly to pull socket switches for incandescent electric lamps.

The main object is to provide a simple, inexpensive and reliable construction which can be readily assembled, adjusted, operated and disassembled and in which there is no danger of short circuiting, grounding or injury from sparking.

In its preferred form the invention is illustrated as applied to a double break pull socket switch. It will be apparent however that the invention is not limited to such constructions.

The improvements herein claimed reside particularly in the construction and method of supporting the movable switch contact member.

The metal parts are carried by a suitable supporting body preferably of insulating material. As porcelain is commonly used for the supporting blocks or bodies of such constructions it is common to refer to them as "the porcelain" or "porcelains" where the block is in two parts and these terms will be used in describing the construction although it should be understood that any equivalent material is intended to be covered by these terms.

Figure 1, is a vertical sectional view and elevation of a lamp socket switch embodying the improvements of my invention, the socket shell, the threaded lamp terminal socket and the insulating fiber being shown in section and the other parts in front elevation. Fig. 2, is a side elevation showing the porcelains and interior parts of the chain guide dotted. Fig. 3, is a plan view, the cap being removed. Fig. 4, is a view of the under side of the upper part of the switch carrying block or porcelain. Fig. 5, is a plan view of the lower porcelain with attached stationary switch contacts. Fig. 6, is a rear view of the lower porcelain showing the central post attached thereto. Fig. 7, is a sectional view of the lower porcelain and switch contacts on the plane of the line X X of Fig. 5. Fig. 8, is a detail perspective view of one of the switch contacts.

Fig. 9, is a plan view of a metal ratchet plate. Fig. 10, is a plan view of an insulating member preferably of porcelain which carries the movable switch contact arms or "switch member". Fig. 11, is a side view of the same showing the switch contact arms in place. Fig. 12, is a bottom view of the same. Fig. 13, is a side view of the porcelain block members showing dotted the electrical connection from one binding post to one of the stationary switch contacts. Fig. 14, is an opposite side view showing dotted the electrical connection from the other binding post to the threaded socket terminal for the lamp. Fig. 15, is a vertical sectional view of the switch construction on the plane of the line Y Y of Fig. 3. Fig. 16, is a horizontal section on the plane of the line Z Z of Fig. 1. Fig. 17, is a drop perspective view showing the separate parts of the mechanism without the shell. Fig. 18, is a detail perspective view of a somewhat modified central post construction.

The shell is of any suitable type consisting preferably of the body 1 which is removably telescoped at its upper end in the cap 2. The switch is operated by means of a cord or chain 3 which is guided in the tube or bell 4 which projects through the shell. The parts of the switch proper are carried by the porcelain body which consists of two parts. The upper part 5 is secured in a suitable manner as will hereinafter appear to the lower part 6. These two parts in the form which I have illustrated have respectively the semi-cylindrical flanges 7 and 8 which serve to form recesses for inclosing the switch contacts. The lower part carries the screw threaded socket 9 which forms one terminal for the lamp and the center spring member 10 forming the central terminal for the lamp. Suitable insulation, for instance, fiber as 1^a may be provided inside of the shell around the porcelains and switch mechanism. The contact wires leading to the socket are secured to the circuit terminals 11 and 12 which are located in recesses in the upper end of the upper porcelain part 5. These terminals are secured in place by screws 13 and 14 respectively which pass through openings 15 and 16 respectively in the upper porcelain and also hold the upper and lower porcelains together. The plate 17 has screw threaded openings 18 and 19 and is secured to the lower porcelain by means of a screw

20 which passes through a hole 20' in the screw threaded socket 9 and the hole 21 in the lower porcelain part 6 and is screwed into the opening 19 in the plate 17. The 5 plate 17 is located in a recess 22 so as to protect and hold it in place. The terminal screw 13 is screwed into the hole 18 in the plate 17 and the upper and lower parts of the porcelain are thus held securely together.

10 The stationary switch contacts 23 and 24 are in the form of curved spring plates each of which has a downwardly and inwardly turned foot such as 25 secured to the lower porcelain 6. The plate 26 has screw-threaded holes or openings 27 and 28. The screw 29 passes through the opening 30 in the lower porcelain, through a hole in the foot 25 of the contact member 23 and is screwed into the hole 27 in the plate 26. This contact 23 and plate 26 are preferably located in the recess 31 to better protect and position the parts. The terminal screw 14 which passes through the hole 16 in the upper porcelain is screwed into the hole 28 of the plate 26 and thus secures the two parts of the porcelain together in much the same manner as the screw 13 and the parts described in connection therewith. The other spring contact 24 is secured to the lower or 25 base porcelain 6 by means of a nut 32 and a screw 33 (see Fig. 7). The contact 24 is located preferably in a recess 34 to better position and protect the parts. The screw 33 also secures the center lamp terminal 10 30 to the base and thus electrically connects the switch contact 24 and the terminal 10. The screw 35 passes through the hole 36 in the socket 9, hole 37 in part 6, and screws into nut 38 in recess 39 to more securely hold the 35 threaded socket 9.

40 The circuit terminal 11 is electrically connected with the lamp terminal 9 by means of the circuit through screw 13, plate 17 and screw 20. The circuit terminal 12 is electrically connected to the switch contact 23 by the circuit including the screw 14 and plate 26. The other switch contact 24 is electrically connected to the center lamp terminal by the screw 33.

45 The stationary switch contacts 23 and 24 are adapted to be connected by means of a rotary switch contact member having the spring arms 40 and 41 which are adapted to engage the switch contacts 23 and 24 and thus bridge the same. The switch contact member is mounted in a recess in the lower part of an insulating member 42 which is formed preferably of porcelain and which may be termed the switch contact member 50 carrier. The switch contact member consists of a plate 43 with the spring arms 40 and 41 integral therewith and having a central opening to fit the square boss 44 in the under side of the carrier so as to rotate with the 55 carrier. The carrier is rotatably mounted

on the rigid central post 45 but the switch contact member is not electrically connected with the post. The post is secured to the boss 6 rigidly and has its upper end free as shown in Figs. 6 and 7. The lower end of the post in the preferred form has a slotted head 46 in a recess in the bottom of the base. A threaded portion 47 passes by through an opening in the base and is engaged by an angular nut 48 which is located in a recess 70 in the upper face of the base 6 so as to be flush with the upper side thereof as shown in Figs. 7 and 17. The post is secured in place by screwing it into the nut 48 after the nut is placed in the recess in the upper face 75 of the base. The post may be removed by unscrewing from the nut 48 and thus releasing it. The upper end of the post 45 extends into an opening 49 in the upper porcelain 5.

80 The switch contact member and carrier 42 are operated intermittently in a left hand direction by means of an oscillating ratchet member 50 and a pull cord or chain 3. The ratchet member 50 has one or more downwardly projecting teeth 52. The carrier 42 85 has a recess in its upper surface with opposing teeth 53. Instead of having the teeth 52 of the ratchet member engage the teeth 53 on the carrier as might be done I prefer to interpose a ratchet plate 54 having downwardly turned teeth such as 55 engaging the carrier teeth 53 and having a central opening 56 engaging the angular boss 57 on the carrier so that the plate and carrier rotate 90 together. The bending down of the teeth 55 leaves shoulders such as 55' which constitute teeth for co-action with the teeth 52 on the ratchet member 50. When the ratchet member is pulled by the chain 3 so as to oscillate left handed it causes a corresponding 95 movement of the carrier and switch contact member.

100 The coil spring 58 which encircles the post 45 has its upper end relatively stationary and its lower end bent into hook form as at 110 59 to engage the shoulder 60 on the operating ratchet member 50 so as to normally press the ratchet member toward the left and return it to that position when released at which time it presses against the shoulder 115 61 of the porcelain (see Fig. 16). When the chain is pulled and the ratchet member oscillates left handed to the right in Fig. 16 the ratchet member engages the shoulder 62 so that the movement is limited.

120 Beneath the upper ends of the inclined spring switch contacts 23 and 24 I prefer to provide shoulders 63 and 64 to prevent the backward rotation of the carrier 42 and switch member arms 40 and 41 when the 125 switch member is in the "off" position. Adjacent the lower ends of the switch contacts 23 and 24 I provide shoulders 65 and 66 on which the switch member arms 40 and 41 rest when in the "off" or "open" position 130

and over which they are caused to ride so that they may snap down on to the switch contacts 23 and 24 as the carrier and switch member are rotated. These shoulders 65 and 66 also prevent backward rotation of the switch carrier and switch member when the contacts are in the "closed" or "on" position.

In order to adjust the spring 58 I provide a sleeve 68 which forms an abutment to which the upper end of the spring 59 is attached. This sleeve fits on the upper end of the post 45 in the opening 49 and has one or more inclined teeth 69 engaging with corresponding ratchet teeth 70 (see Fig. 4) formed in the under surface of the upper porcelain part 5. The parts are assembled on the post 45 in their proper order, the spring 58 being loose. The sleeve is then simply rotated by a suitable instrument from the top of the upper porcelain (see Fig. 3) so as to tighten the spring 58 to the desired extent.

The chain is attached to the under side of the ratchet member 50 and runs around one side of the carrier 42 resting on the flange 8 of the lower porcelain inside the fiber lining 1^a. The chain guide bell 4 is attached to a plate 72 located inside of the socket shell and the shank 73 of the bell projects through a slot 74 in the body 1 of the shell just beneath the lower edge of the cap 2 of the shell. The plate 72 is held between the insulating fiber 1^a and the porcelain switch carrying block as shown in Figs. 1 and 16. To more securely position the bell I provide the plate 72 with upwardly projecting fingers 75 and 76 which embrace the sides of the lug 77 on the periphery of the upper porcelain 5 and the lug 77 projects into the slot 74 in the shell above the body of the plate 72. This prevents the plate from turning. When the cap 2 is removed from the body of the shell the entire switch mechanism may be removed by lifting the bell 4. When the parts are removed from the shell the plate 72 is simply held loosely in position by the lug 77, the chain guide not being attached either to the shell or to the porcelain but simply held in place by the relative position of the parts. This construction is very easy to assemble.

Instead of having the head of the rigid post 45 integral with it as shown in Fig. 7 it may be separate as shown in Fig. 18. The post is screw threaded at 47' at the lower end and the two nuts 46' and 48' are provided for engaging the lower and upper surfaces of the base part 6 of the porcelain. Other changes if desired in the construction may be made without departing from the spirit or scope of my invention. The rigid post holds the parts in proper alinement and also makes it very easy to assemble them.

From the foregoing it will be noted that

the switch parts are completely insulated from the shell and the operating chain is not electrically connected to any current carrying member. There is therefore no possibility of any grounding or leakage of current.

The features of the chain guide construction are claimed in my application #639,522 filed July 20, 1911.

What I claim is:—

1. In a pull switch, an insulating base formed of two separable parts, a spindle passing through one part and having a head on one side of said part and a nut on the other side of said part clamping said spindle rigidly to said part, the other end of said spindle extending into proximity to the other part of said base, and a switch member, a lever, a spring and an abutment on said spindle and all removable from said spindle when the parts of said base are separated.

2. In a pull switch, an insulating base with a spindle opening, a spindle extending through said opening and having a head on one side of said base and a nut screwed onto the spindle on the other side of said base clamping said spindle rigidly to said base, a switch contact secured to said base adjacent said spindle, a rotatable switch member on said spindle, an oscillating ratchet lever on said spindle, a spring on said spindle and a movable abutment for the outer end of said spring, said rotary switch member, said lever and said spring being readily removable from said spindle without disturbing said spindle when said abutment is removed.

3. In a pull switch, an insulating base with a spindle opening, a one-piece spindle extending through said opening and having a head on one side of said base and a nut screwed on to the spindle on to the other side of said base and clamping said spindle rigidly to said base, switch contacts secured to said base on opposite sides of said spindle, a switch member on said spindle but insulated therefrom and adapted to connect said contacts, an oscillating operating lever mounted on said spindle, removable means for holding said switch member and said operating lever on said spindle and lamp terminals secured to said insulating base and insulated from said spindle, one of said lamp terminals being electrically connected to one of said contacts.

4. In a pull switch, an insulating base with a spindle opening, a spindle extending through said opening and having a head on one side of said base and a nut on the spindle on the other side of said base clamping said spindle rigidly to said base, switch contacts secured to said base on opposite sides of said spindle, a switch member on said spindle adapted to connect said

- contacts, an oscillating operating lever on said spindle for moving said switch member and removable means for securing said operating lever and said switch member on said spindle, a pull chain connected to said operating lever, circuit terminals secured to said insulating base and insulating flanges carried by said base guarding said chain from said circuit terminals and from 10 said contacts.
5. In a pull switch, an insulating base having a spindle passage with recesses at opposite ends of the spindle passage, a spindle extending through said passage and having a slotted head in one recess and a nut clamped in the opposite recess, a switch contact secured to said base adjacent said spindle, a rotary switch member and an operating lever removably mounted on said spindle, and a detachable abutment for securing said switch member and said lever on said spindle, said switch member and lever being adapted to be placed on said spindle or removed from said spindle, when 20 said securing abutment is detached, without disturbing said spindle.
- 15 6. In a pull switch, an insulating block, a post having one end rigidly clamped thereto, a switch contact mounted on said block, a rotatable insulating disk on said post, a switch member carried thereby and insulated from said post, said insulating block and disk surrounding said switch contact, an operating lever mounted on said post and 30 coacting with said insulating disk, a helical spring on said post engaging said lever and a chain for oscillating said lever.
- 25 7. In a pull switch, a two-part insulating block, a post rigidly clamped to one part, an insulating disk rotatably mounted on said 35 post, a switch member carried by said disk, an oscillating operating lever mounted on said post, and coacting with said disk and an operating chain secured to said operating lever and extending part way around said 40 insulating disk between the two parts of said insulating block, said insulating block and disk surrounding said switch member.
8. In a pull switch, two insulating blocks forming a base, means for detachably securing said blocks together, a spindle passing through one block and having a head on one side of said block and a nut screwed on to said spindle on the other side of said block and clamping one end of said spindle rigidly 45 to said block, the other end of said spindle extending into proximity to the other insulating block and switch operating mechanism mounted on said spindle and readily removable from said spindle without disturbing said spindle when the parts of said base are separated.
- 50 9. In a pull socket, an insulating block having a spindle passage and a recess in its inner face around said passage, a spindle extending through said passage and having a head at the outer face of said block and a nut held in said recess through which said spindle is screwed, said spindle being supported wholly by said block, a second 55 insulating block detachably secured to the first mentioned block and switch mechanism mounted on said spindle between said block and removable from the outer end of said spindle without disturbing said spindle, 60 when said blocks are separated.
- 55 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315
